UNITED STATES PATENT OFFICE.

CHARLES FISHER, OF LYONS, NEW YORK, ASSIGNOR OF ONE-HALF TO
GEORGE A. HORN, OF NEWARK, NEW YORK.

END-GATE FOR WAGONS.

SPECIFICATION forming part of Letters Patent No. 712,284, dated October 28, 1902.

Application filed August 9, 1902. Serial No. 119,066. (No model.)

To all whom it may concern:

Be it known that I, CHARLES FISHER, of Lyons, in the county of Wayne and State of New York, have invented a new and useful 5 Improvement in End-Gates, which improvement is fully set forth in the following specification and shown in the accompanying drawings.

My invention relates to end-gates and chutes 10 to be attached to a wagon-box, the invention being an improvement upon the device shown and described in Patent No. 701,320, granted to me June 3, 1902.

One object of my present invention is to 15 produce an end-gate having two or more slideable or telescoping sections which may be closed together or massed to act as an end-board for the box or drawn out or extended to act as a chute or skid.

Another object of the invention is to 20 provide means for holding and locking the device in position when acting as an end-board.

A further object of the invention is to provide holders at the side of the box and form 25 the first or primary slideable section of the end-gate with hooks to pass onto said holders, so the telescoping sections may act as a chute at the side of the box.

Other objects and advantages of the invention 30 will be brought out and made to appear in the following specification, reference being had to the accompanying drawings, forming a part thereof, the invention being particularly pointed out in the claims.

Figure 1 is a side elevation of a part at the 35 rear end of a wagon-box, showing my improved device in place thereon, parts being shown in various positions by full and by dotted lines. Fig. 2 is a plan of the rear part of 40 the wagon-box, showing the end-gate attached at the side. Fig. 3 is a plan of the end-gate drawn out to act as a lengthened skid, seen as indicated by arrow 3 in Fig. 1, parts being broken away and omitted. Fig. 4 is a side 45 elevation of parts, better showing the manner of actuating the notched hangers and of controlling the device when serving as an end-board, parts being shown in various positions by full and by dotted lines. Fig. 5 is a rear side elevation of a part of the device, indicated by arrow 5 in Fig. 4, further showing the construction. Fig. 6, detached, fur-

ther shows in side elevation the form of a side of the primary sliding section, a part being broken out. Fig. 7 is a plan of a part of 55 the wagon-box and associated parts, showing the manner of hanging the sliding sections at the side of the box, parts being broken away, the view being the same as in Fig. 2. Figs. 4 to 7, inclusive, are drawn to a scale 60 larger than that of the remaining figures.

A in the drawings is the wagon-box, B being my improved end-gate secured to the box. This end-gate comprises a main part or body C, formed of a sheet-metal plate d with upturned sides b and constructed in every other way like the corresponding part B shown and described in said Letters Patent No. 701,320. The body C is formed with a tubular hinge part f, holding a removable hinge-rod k, which 70 passes through the ends of straps h h, secured to the sides of the wagon-box, as shown in said patent, admitting the end-gate to swing in a vertical plane. Notched hangers l l are secured pivotally to the sides b b of the body 75 C, passing through controlling-loops m m, secured at the sides of the wagon-box to determine the positions of said body C, as set forth in said former patent.

The end-gate B is made up of three main 80 parts or sections C p t, all of sheet metal, the sections p and t being formed with upturned sides o and r, respectively. The primary section p is fitted to slide or telescope within the main section C, the secondary section t 85 similarly telescoping within the primary section p, the three sections being shown in full lines in Fig. 1 as drawn out or extended and in dotted lines as slid together or bunched.

The wagon-box is formed with an opening 90 D through its side, out through which to deliver the contents of the box when convenient or desirable to do so, provision being made to shift the end-gate, or sections thereof, to a position beneath the opening. Rests or lugs 95 s s, Figs. 1 and 2, are secured to the box A adjacent to the opening D in positions to receive the hinge-rod k, as shown by dotted lines in Fig. 1. When the end-gate as a whole is shifted to the side of the box, the 100 tubular part f of the section C occupies a position between and in line with the lugs s s, the rod k passing through all three parts. I prefer, however, to construct the device so

the primary section *p* of the end-gate may be drawn out of the main section *C* and shifted to the side of the wagon-box, leaving said main section undisturbed in place to continue 5 to act as end-board for the box. For this purpose I extend the sides *o o* of the section *p* slightly beyond the floor of the section to form hooks *u u*, Figs. 3 and 6, to pass upon pins *v v*, Fig. 7, secured in horizontal positions to the 10 box *A*, these pins being substituted for and in the place of the lugs *s s*.

To conveniently raise the hangers *l l* to release them from the holding-loops *m* for the purpose of allowing the end-gate to swing 15 back or down from the wagon-box, I have provided a bent shaft *w*, Figs. 1, 4, and 5, held in bearings *c*, secured to the rear face of the section *C* of the end-gate. The ends of this shaft are bent forward near the sides *b b* 20 of the end-gate and connected by straps or links *a a* with the respective hangers *l l* forward of their pivot-bearings *n*. The shaft is also formed with a laterally and downwardly extended part *e*, constituting a handle or lever 25 by which to turn the shaft in its bearings. From the construction shown it will be understood that by pressing the handle *e* toward the adjacent surface of the end-gate the hangers *l l* will be raised to clear the loops *m m*, as 30 shown by dotted positions of parts in Fig. 4, and allow the end-gate to swing away from the end of the box *A*. Provision is also made to lock the end-gate in vertical position to close the rear end of the box *A*, when it acts 35 as an end-board. The extended part or handle *e* of the shaft *w* holds a pivotal lever or stop *g* in position to have its inner short end bear against the plate *d* of the end-gate, as shown in Fig. 4, when turned to a horizontal 40 position. This serves to cause the extreme ends of the shaft to press the links *a a* down against the hangers *l l*, and so hold the hangers in engagement with the respective loops *m m* and keep the end-gate in place against the 45 wagon-box. The handle *e* being at the rear of the end-gate enables one standing at the rear end of the wagon to conveniently control the hangers, and so either lock the end-gate in its vertical position or free it for the 50 purpose of turning it back from the end of the wagon-box.

What I claim as my invention, and desire to secure by Letters Patent, is—

1. An end-gate and chute for wagons, consisting of a sheet-metal body or holder joined to the wagon-box by a flexible hinge, and telescopic extension pieces or sections held by said body and adapted to slide one within another to lengthen the chute, or to be closed 55 within the body, and means for controlling the body, substantially as set forth.

2. In combination with a wagon-box having rests at its end and at the side, an end-gate and chute formed in telescopic sections with 55 tubular part to coact with said rests, and a hinge-rod adapted to pierce said rests and the tubular part of the end-gate, the wagon-box

having an opening at its side to coact with the end-gate, and means for controlling the end-gate at the end of the box, substantially as shown and described. 70

3. An end-gate for wagons, consisting of a plate joined to the wagon-box in flexible joint, said end-gate being constructed in telescopic sections and arranged to act either as 75 an end-board or as a chute, a pair of notched hangers on the end-gate controlled by holding-loops at the sides of the box, and means at the rear side of the plate to lock the hangers, substantially as and for the purpose set forth. 80

4. A wagon end-gate consisting of a sheet-metal body or plate held to the wagon-box in a flexible joint to act as an end-board, a removable sheet-metal section held to slide within said metal body or plate, rests on the 85 wagon-box, and parts of said removable section adapted to be engaged by said rests, the side of the wagon-box having an opening adjacent to the rests, substantially as and for the purpose set forth. 90

5. A wagon end-gate consisting of a sheet-metal body or plate held to the wagon-box in a flexible joint to act as an end-board, a removable sheet-metal section held to slide within said metal plate, rests on the wagon-box, and parts of said section adapted to be engaged by said rests, the side of the wagon-box having an opening adjacent to the rests, and an extensible section held to slide within said removable sheet-metal section, substantially as shown and described. 95 100

6. An end-gate for wagons, consisting of a plate joined to the wagon-box in flexible joint and constructed in telescopic sections to act either as an end-board or as a chute, a pair of notched hangers on the end-gate controlled by holding-loops at the sides of the box, and means at the rear side of the plate to release the hangers from the holding-loops, substantially as and for the purpose specified. 110

7. A combined end-gate and chute for wagons, the same comprising telescopic sections with upturned sides, means for pivotally supporting the end of the section adjacent the wagon-box, means for holding said section in an inclined position with the section distended and also for holding it in a vertical position with the sections closed within each other to form an end-gate, substantially as described. 115 120

8. A combined end-gate and chute for wagons, the same comprising telescopic sections with upturned sides, means for pivotally supporting the end of the section adjacent the wagon-box, means for holding said section in an inclined position with the section distended and also for holding it in a vertical position with the sections closed within each other to form an end-gate, a bent shaft held in bearings on the end section of the gate, 130 straps connecting the said shaft with hangers pivoted on the section, said shaft having lateral and downwardly-extended part to form a handle. 125

9. A combined end-gate and chute for wagons, the same comprising telescopic sections with upturned sides, means for pivotally supporting the end of the section adjacent the wagon-box, means for holding said section in an inclined position with the sections distended and also for holding it in a vertical position with the sections closed within each other to form an end-gate, a bent shaft held

5 in bearings on the end section of the gate, straps connecting the said shaft with hangers

pivoted on the section, said shaft having a lateral and downwardly-extended part to form a handle, and a pivoted stop mounted on said handle.

In witness whereof I have hereunto set my hand, this 30th day of July, 1902, in the presence of two subscribing witnesses.

CHARLES FISHER.
